UNITED STATES PATENT OFFICE.

GEORGE F. COFFELT, OF DAYTON, OHIO.

ROTARY ENGINE

1,404,583.

Specification of Letters Patent. Patented Jan. 24, 1922.

Application filed November 15, 1920. Serial No. 424,364.

To all whom it may concern:

Be it known that I, GEORGE F. COFFELT, a citizen of the United States, residing at Dayton, in the county of Montgomery and State of Ohio, have invented new and useful Improvements in Rotary Engines, of which the following is a specification.

The object of my present invention is the provision of a rotary engine characterized by simplicity and durability and the capacity of work reliably in the development of considerable power in proportion to its size.

To the attainment of the foregoing, the invention consists in the improvement as hereinafter described and definitely claimed.

In the accompanying drawings, forming part hereof:—

Figure 1 is a view showing my novel engine or apparatus in side elevation.

Figure 2 is a plan view illustrative of the lower section of the piston cylinder and the piston therein.

Figure 3 is an inverted plan of the upper section of the piston cylinder.

Figure 4 is a view partly in side elevation and partly in vertical section, the section being taken in a plane parallel to Figure 1.

Figure 5 is a detail section illustrating the means for automatically controlling the supply of fluid under pressure to the cylinder.

Figure 6 is an enlarged detail section showing one of the relief valves of the rectilinearly movable piston blade.

Figure 7 is an enlarged broken view in plan showing a part of the means to control the supply of fluid under pressure to the cylinder.

Figure 8 is a detail enlarged view of the air compressing means comprised in the improvement.

Similar numerals of reference designate corresponding parts in all of the views of the drawings.

The illustrated embodiment of my invention is of internal combustion type, and among other elements the said embodiment comprises a lower cylinder section 1 and an upper cylinder section 2, the latter being interiorly channeled as indicated by 3 to afford an explosion chamber that is traversed by the extended portion of the rectilinearly movable blade 4 of the rotary piston 5. The rotation of the piston 5 in conjunction with the cylinder controls the rectilinear move-

ments of the blade 4, and it will be observed by comparison of Figures 4 and 6 that each end portion of the blade 4 is provided with what I designate a relief valve 6. The said relief valves 6 are provided in order to facilitate starting of the engine, and it will be readily understood in this connection that if a vacuum is created in the explosion chamber 3 back of the extended portion of the blade 4 when the engine is idle, the said vacuum will be broken by the opening of the uppermost valve 6 at the initial movement of the piston in the direction indicated by arrow in Figure 4. Interiorly the piston cylinder is provided with a cam portion 7 for cooperation with the beveled ends 8 of the blade 4, and at 9 the cylinder is provided with an exhaust conduit in communication with the atmosphere. It will also be understood by comparison of Figures 2, 4 and 5 that the piston 5 is provided with peripheral recesses 10.

Appropriately connected with and supported by the piston cylinder is a cylinder 11, Figures 1, 4, 5 and 7 in which is a piston valve 12 for controlling the supply of fluid under pressure to the cylinder of the working piston. The said piston valve 12 is provided with a stem 13 that extends into the cylinder of the piston 5 and is controlled by the said piston 5. In other words when the stem 13 is opposed to the unrecessed portions of the piston 5, the valve 12 will be in its outermost position while when the stem 13 is opposed to one of the recesses 10 the spring 14 at the right of the piston valve 12 will be enabled to force the said piston valve 12 toward the left. The apertures 15 at the right hand end of the cylinder 11 are merely vents to prevent a cushion of air from interfering with movement of the piston valve 12 toward the right. The said piston valve 12 is characterized by a transverse port or chamber 16, and it will also be observed that a conduit 17 leads from one side of the cylinder 11 to the cylinder of the working piston 5 at the point 18 in Figure 4. Connected to one side of the cylinder 11 is a pipe 19 adapted to lead from a source of gasoline or other hydrocarbon fuel supply and provided with a regulating valve 20. Also leading from said side of the cylinder 11 and arranged in transverse alignment with the mouth of the conduit 17 is a pipe 21, Figures 1, 4 and 7. The said pipe 21 extends laterally from the cylinder 11 and then

upwardly, and at its end remote from the cylinder 11 said pipe 21 is connected with a compressed air tank 22, Figures 1 and 4. Connected at 23 with the interior of the cylinder of the working piston 5 is a pipe 24, Figures 4 and 8, which leads to one end of a pump cylinder 25 in which is a piston 26 that is movable by the expanding mixture toward the left in Figure 8 against the action of a spring 26 also contained in the cylinder 25. The expanding products of combustion act of course against the piston 26 to move the same toward the left in Figure 8. When the piston 26 is moved toward the right in Figure 8 it serves to draw atmospheric air into the cylinder 25 past the inwardly opening non-return valve 27, and when the piston 26 is moved toward the left in Figure 8 it serves to compress such air and to force the same past the non-return valve 28 and through the conduit 29 into the storage tank 22.

Any appropriate ignition means may be employed, though I prefer to use a spark plug 30 and to control the creation of sparks by the ordinary well known means associated with the working piston 5.

In the practical operation of the embodiment illustrated and described it will be manifest that when the piston valve 12 is in the position shown in Figure 7 hydrocarbon fuel will be received in the chamber 16. When one of the piston recesses 10 is presented to the stem 13, the spring 14 will move the piston 12 and interpose the chamber 16 and the fuel charge therein between the pipe 21 and the conduit 17 whereupon a head of fluid under pressure will sweep with the fuel charge through the conduit 17 and into the cylinder of the working piston 5. The charge will then be ignited by the explosion 30 and the working piston will be rotated in the direction indicated by arrow in Figure 4. As the extended portion of the piston blade 4 passes the port 23 and after such passage and before the extended portion of the piston blade 4 reaches the exhaust conduit the expanding products of combustion will operate to force the piston 26 toward the left in Figure 8, and in that way will replenish the supply of compressed air in the tank 22. After the extended portion of the piston 4 passes the exhaust port or conduit 9, the spring 26 will operate to move the piston 26 toward the right in Figure 8 with the result that atmospheric air will be drawn into the cylinder 25, ready to be forced into the tank 22 on the subsequent movement of the piston 26 toward the left in

Figure 8. The operation described will continue so long as hydrocarbon fuel is supplied through the pipe 19, and when the supply of hydrocarbon fuel is cut off the engine will come to a stop.

It will be apparent from the foregoing that my novel engine is capable of reliable operation, the cam 7 in cooperation with the beveled ends 8 of the piston blade 4 serving to correctly position the said blade 4 at each time when one end of the blade is in a position in front of the explosive mixture supply port 18, with reference to the direction of rotation of the working piston 5. It will also be apparent that the engine is simple, and that all of its parts are well adapted to withstand the usage to which apparatus of corresponding character is ordinarily subjected.

While designed primarily as an internal combustion engine, it is to be understood that some of the features of my novel engine may be used to advantage in a steam engine.

Having described my invention, what I claim and desire to secure by Letters-Patent, is:—

1. The combination of a rotary internal combustion engine comprising a cylinder and a rotary piston with peripheral recesses, disposed in said cylinder, a piston valve having a stem extending into the cylinder and opposed to the periphery of the piston and adapted to cooperate with the piston recesses, said piston valve also having a transverse port, a casing containing said valve, a pipe leading from the valve casing and adapted to be connected with a source of fluid-pressure supply, a pipe connecting said valve casing and the cylinder, the induction end of said pipe being arranged opposite the end of the fluid-pressure supply pipe, a valved fuel supply pipe leading to the valve casing and arranged outwardly beyond the fluid-pressure supply pipe, and a spring interposed between the outer end of the piston valve and an abutment in the outer portion of the valve casing and adapted when one of the piston recesses is opposed to the valve stem to press the piston valve inwardly.

2. In a rotary engine, the combination of a cylinder having induction and exhaust ports and an internal cam portion adjacent to the exhaust port, a rotary piston in said cylinder, a blade carried by and movable rectilinearly in the piston and beyond the periphery thereof and relief valves in the end portions of the blade and movable with the blade into and out of the rotary piston.

In testimony whereof I affix my signature.

GEORGE F. COFFELT.
